TOY CRANE

Fred H. Stickle, Cleveland Heights, Ohio

Application April 24, 1948, Serial No. 23,031

15 Claims. (Cl. 212—21)

1

This invention relates to improvements in toy cranes, more particularly toy cranes of the overhead traveling type intended for use in connection with miniature electric railway systems.

One of the objects of the invention is the provision of a crane of this type employing a single electric motor for propelling the crane car and operating a hoist carried by the car.

Another object is the provision of remote control means for governing the action of the crane to propel the car in either direction and operate the hoist up or down, and for interrupting their action at will.

Another object is the provision in such a crane of a lifting magnet operated by the hoist under a remote control separate from and independent of the car and hoist controls.

Still another object is the provision of simple gear shift mechanism operated electrically under remote control for driving the car propelling means or hoist operating means selectively.

Other objects and features of novelty will appear as I proceed with the description of those embodiments of the invention which, for the purposes of the present application, I have illustrated in the accompanying drawings, in which

Fig. 1 is a perspective view of a crane embodying the invention.

Fig. 2 is a plan view of the principal operating mechanism, certain parts being removed to better illustrate the invention.

Fig. 3 is a detail perspective view of a portion of the car propelling means.

Fig. 4 is a detail perspective view of a portion of the hoist operating means.

Fig. 5 is a detail sectional view taken substantially on the line 5—5 of Fig. 2.

Fig. 6 is a vertical sectional view taken substantially on the line 6—6 of Fig. 1 and showing the parts on an enlarged scale.

Fig. 7 is a fragmental plan view on an enlarged scale showing a modified form of drive and gear shift mechanism.

Fig. 8 is an elevational view of the same, partially in section on the line 8—8 of Fig. 7, and

Fig. 9 is a wiring diagram.

Referring to Fig. 1, 10 and 11 are two spaced trestles which may be mounted upon blocks 12 and 13 for the sake of stability. At their upper ends the trestles are joined by suitable overhead beams 14. These beams carry brackets 15 upon which are mounted and clamped track rails 16 and 17, insulation 18 being interposed between the rails and the brackets.

The crane car travels upon rails 16 and 17. It 55

2

comprises two trucks 19 and 20, one on each side of the car, these trucks being attached to a plate 21 of insulation material. Each truck comprises an anglebar 22 extending beneath insulation plate 21 and secured thereto by means of a bolt 23. Anglebar 22 carries a pair of spaced truck bars 24, between which are supported pivots for two wheels 25. The bolt 26 which supports bars 24 from anglebar 22 may also carry a resilient metal brush 27 to insure good electrical connection between the truck and the rail.

Insulation plate 21 is bored to receive a bolt 30. Surrounding that bolt above plate 21 there is a spacing sleeve 31. A nut 32 threaded on the bolt 15 bears upon sleeve 31 to take the load of the car parts suspended by the bolt 30. Beneath plate 21 a second sleeve 33 surrounds bolt 30. A bracket 34 of inverted U-shape is suspended beneath sleeve 33 by a nut 35 threaded upon the lower end 20 of the bolt which projects through a hole 29 in the bracket. A second bracket 36 of peculiar form best illustrated in Fig. 3 is provided with a slot 37 loosely receiving sleeve 33. Bracket 36 rests upon bracket 34 and may have a limited amount 25 of movement longitudinally of the track relative to bracket 34. In the depending arms of bracket 34 there is journaled a shaft 38 upon which is wound a cable 39, this shaft and cable constituting the crane hoist.

Near the upper ends of the trestles 10 and 11 30 there are cross braces 40 and 41 which are perforated to provide bearings for a screw shaft 42 and a square shaft 43. An internally threaded cylinder 44 hereinafter referred to as a nut cooperates with the threads on screw shaft 42. On 35 the square shaft there is slidably mounted a worm 45 provided with a square hole to receive shaft 43, so that the worm turns with the shaft but is free to move longitudinally upon it. While the shaft 43 is illustrated and referred to herein as 40 a square shaft, that term is intended to include any form of shaft which will transmit rotation to worm 45 while permitting travel of the worm upon the shaft. Bracket 36 has arms 46 which 45 are soldered or otherwise joined to the ends of nut 44, so that the nut will be held against rotation and so that the bracket will move with the nut when the latter is impelled in one direction or the other by screw shaft 42. A yoke 47 secured to bracket 34 embraces the ends of worm 45 and thereby causes it to travel with the car lengthwise of the shafts. On one end of shaft 38 there is a worm wheel 48 which meshes with worm 45 for operation of the hoist. A pair of fingers 49 attached to yoke 47 serve to guide cable 39, and

additionally to form an abutment for a washer 50 surrounding the cable above a coil spring 51 which bears at its lower end against the upper surface of an electrically energized lifting magnet 52. It is therefore impossible for the heavy lifting magnet to strike sharply against the fingers 49 at the top of its travel, for the spring 51 brings it to a gradual stop.

Supported upon the cross brace 40 by bolts 53 and 54 are two electromagnets 55 and 56. A bracket 57 welded or soldered to brace 40 carries a pin 58 upon which an armature 59 is pivoted. At the ends of armature 59 there are hinged two angular arms 60 and 61, the inturned ends of which are provided with holes loosely receiving the shafts 42 and 43. Collars 62 and 63 are pinned to the shafts between the arms 60 and 61 and the adjacent ends of the shafts. The energization of one of the electromagnets 55 and 56 will swing armature 59. This results in moving the shafts 42 and 43 lengthwise in opposite directions. Fig. 2 for example shows the result of energizing magnet 55. This causes armature 59 to engage the extremity of shaft 42 and push the shaft toward the right. At the same time the in-turned end of arm 61 by engagement with collar 63 pulls shaft 43 toward the left.

Shafts 42 and 43 at their right-hand ends have bevel gears 65 and 66 pinned thereto. These gears are adapted to mesh with bevel gears 67 and 68 respectively pinned to the outer ends of shaft 69. The latter shaft is driven through a set of reduction gears 70, 71 and 72, the latter gear being fixed to the shaft of a reversible electric motor 73. Hence by the selective energization of one or the other of electromagnets 55 and 56 either one of the shafts 42 may be shifted toward the right to bring its bevel gear into mesh with the corresponding bevel gear of transverse shaft 69, while the bevel gear of the other shaft is withdrawn from driving relation with shaft 69. The motor therefore can be caused to drive either shaft while the other remains stationary, and since the motor may be reversed either shaft may be turned in either direction.

Current for the energization of the lifting magnet 52 is supplied through a pair of flexible conductors 75 and 76 which extend upwardly to the bolts 23 of the car, and then through the trucks 19 and 20 to the rails 17 and 18. To the right hand ends of the rails there are soldered conductors 77 and 78 which extend down through an insulating tube 79 along with other conductors to a multipoint socket in block 13. A corresponding multipoint plug 80 on the end of a multiwire flexible cord 81 can be removably mounted in this socket for connection with a control panel presently to be described. In the circuit for the lifting magnet there is a signal lamp 74.

Current for the electromagnets 55 and 56 is supplied by two conductors leading to the magnets and a return conductor, all three conductors being accommodated in a piece of insulation tubing 82 clamped to one of the beams 14. These conductors also extend downwardly through insulation tube 79 along with four conductors for the motor.

Figs. 7 and 8 illustrate a modified form of gear shift for selecting drive from the motor to one or the other of shafts 42 and 43. In this case the shaft of motor 73' carries a worm 85 which meshes with a worm wheel 64 slidably keyed to a transverse shaft 69' having bevel gears 67' and 68' on its ends adapted to engage one at a time with bevel gears 65 and 66 on the shafts 42 and 76.

53. Shaft 69' is slidably and rotatably mounted in ears 86 struck out from one of the housing plates 87 of the motor, and slides within worm wheel 64 which is held against lengthwise movement with the shaft by the arms of a U-shaped bracket 74' soldered to housing plate 87.

A yoke 88, the upwardly extending arms of which are perforated to receive loosely shaft 69', engages the hubs of bevel gears 67' and 68', so that any motion of the yoke transversely of the crane is communicated to shaft 69'. Fixed upon yoke 88 is a depending armature 89 disposed between a pair of aligned electromagnets 55' and 56' which are also supported upon housing plate 87. For the purpose of guiding yoke 88 I may mount a metal band 90 upon one of the electromagnets, the ends of the band being directed upwardly on opposite sides of the yoke. Obviously when one of the electromagnets 55' and 56' is energized the armature 89 will be attracted and the yoke 88 will shift transverse shaft 69' to cause one of the bevel pinions 67' or 68' to move into mesh with the corresponding bevel pinion on the shaft 42 or 43, as the case may be. 25 In this instance the two latter shafts are held against longitudinal movement by suitable means such as collars 91 pinned to the shafts on opposite sides of brace 41.

At the upper end of bolt 30 I mount a cap 92 30 having a perforation receiving the projecting upper end of the bolt. A nut 93 threaded on the end of the bolt serves to hold the cap removably in place. In the first described form of the invention the electromagnets 55 and 56 with their armature and associated parts may be covered by a casing 94 removably attached by any suitable means to the trestle 10. At the opposite end of the crane a casing 95 removably attached to trestle 11 conceals and protects the motor, the transverse shaft 69 and the gearing for driving the latter shaft. This casing may have a window therein through which the signal lamp 74 is visible, as illustrated in Fig. 1. A similar housing may be used to protect and conceal the motor and gear shift mechanism of the second 45 described form of the invention.

In Fig. 9 a control panel is indicated at 95. Upon it I mount a single pole, single throw switch 96 for controlling the lifting magnet circuit, a 50 single pole, double throw switch 97 for selectively conducting current through one or the other of gear shifting electromagnets 55 and 56, and a double point, double throw switch 98 for reversing the current through motor 73 or 73' as the 55 case may be. On the control panel there is mounted also a push button switch 99 for stopping and starting the motor. 100 and 101 represent binding posts to which are to be connected the low voltage side of a step-down transformer.

60 Two conductors 102 and 103 extend from the brushes of motor 73 to the reversing switch 98. Current enters the latter switch through conductors 78 and 104 and leaves through a conductor 105 which extends to one of the field terminals of the motor. From the other field terminal a conductor 106 leads to like ends of the coils of the two electromagnets 55 and 56. From the opposite ends of these coils conductors 107 and 108 lead to opposite points of the double 65 throw switch 97, while from the pivot point of that switch a conductor 109 extends to one binding post of push button 99. The other post of the push button is connected by a conductor 110 with switch 96 and by conductor 111 with terminal 100.

The operation of the mechanism by means of the illustrated controls is simple and effective. Assuming that the selector switch 97 is set to cause energization of electromagnet 55 by way of conductors 107 and 106, and that the reversing switch 98 is set to produce rotation of the motor shaft in a given direction, then as soon as the operator closes push button switch 99 armature 59 will be swung to the position illustrated in Fig. 2 and shaft 42 will be pushed to the right to cause bevel pinions 65 and 67 to mesh. The resulting rotation of shaft 42 will function through the nut 44 to drive the car in a direction determined by the direction of rotation of the shaft.

When the car has traveled to the desired point the operator opens push button switch 99 and the motor stops. He may then throw switch 97 to the opposite position, after which he may close push button switch 99 causing magnet 56 to be energized through conductors 108 and 106, which will swing armature 59 from the illustrated position of Fig. 2 to its opposite extreme, thereby pulling shaft 42 to the left to disengage gears 65 and 67 and pushing shaft 43 toward the right to cause gears 66 and 68 to mesh. Worm 45 will thus be turned, which will rotate worm wheel 48, thereby turning shaft 38 slowly and either winding up or unwinding cable 39 depending upon the direction of rotation of the motor and the consequent rotation of shaft 43. Assuming that the direction is such as to lower magnet 52, the operator may continue the lowering operation of the hoist until the lifting magnet is directly above some object made of ferrous metal which the operator desires to move. He then opens the push button switch, which stops the operation of the hoist. The operator can then close switch 96, which will energize magnet 52 and signal lamp 74. The lifting magnet will then grip the object to be moved. The operator may now throw the reversing switch 98 to the opposite position and close push button 99, when the hoist will operate to raise the lifting magnet and the object held thereupon. Having completed the upward movement of the lifting magnet to the desired extent the operator may open the push button switch, throw the selector switch 97 to the other position, thereby again bringing the gears 65 and 67 into mesh, when the car may be caused to travel in one direction or the other as desired. By operations which will now be obvious the load may be carried to the desired point, lowered by the hoist and released by opening the switch 96. While the use of a lifting magnet on the lower end of cable 39 is preferred, any type of load support such as a hook may be substituted therefor.

The operation of the gear shift of the second form of the invention functions in a similar manner, as will be readily understood. The movement of transverse shaft 69' in one direction or the other will cause the wide faced worm wheel 64 to slide through the teeth of worm 85, there being sufficient play in these gears to permit such action whether or not the worm is turning at the time.

Having thus described my invention, I claim:

1. In a toy crane, a square shaft and a screw shaft rotatably mounted in parallel relation, a motor, driving connections from said motor comprising clutch means selectively operable by remote control for turning one or the other of said shafts, a car having a non-rotating nut for engagement with said screw shaft to move the car lengthwise of said shafts, a gear slidably and

non-rotatably mounted on said square shaft, said car also having a yoke embracing said gear, whereby the gear travels with the car, a hoist carried by said car, and hoist operating mechanism driven by said gear.

2. In a toy crane, a square shaft and a screw shaft rotatably mounted in parallel relation, a motor, driving connections from said motor comprising clutch means selectively operable by remote control for turning one or the other of said shafts, a car having a non-rotating nut for engagement with said screw shaft to move the car lengthwise of said shafts, a worm slidably and non-rotatably mounted on said square shaft, said car also having a yoke embracing said worm, whereby the worm travels with the car, and said car having a worm wheel in mesh with said worm, a shaft journaled in said car upon which said worm wheel is fixed, a cable wound upon said last named shaft, and a load supporting element at the lower end of said cable.

3. In a toy crane, a square shaft and a screw shaft rotatably mounted in parallel relation, a motor, a transverse shaft disposed at one end of said crane and driven by said motor, bevel gears on the ends of said transverse shaft, a bevel gear on the adjacent end of each of said square and screw shafts, remote control means for selectively causing one only of said last named bevel gears to mesh with a bevel gear on said transverse shaft, a car having a non-rotating nut for engagement with said screw shaft to move the car lengthwise of said shafts, a gear slidably and non-rotatably mounted on said square shaft arranged to move with said car, a hoist carried by said car, and hoist operating mechanism driven by said gear.

4. A toy crane as defined in claim 3, characterized in that said transverse shaft is mounted to slide lengthwise and in that the meshing of one or the other of a pair of bevel gears is effected by shifting said transverse shaft longitudinally.

5. A toy crane as defined in claim 3, characterized in that said square shaft and said screw shaft are mounted to slide lengthwise and in that the meshing of one or the other pair of bevel gears is effected by shifting said square and screw shafts in opposite directions simultaneously.

6. A toy crane as defined in claim 1, wherein said remote control means comprises an electromagnet and a shift mechanism adapted to be operated by said electromagnet, an electric circuit for said electromagnet, and a manual switch controlling said circuit.

55 7. In a toy crane, two spaced trestles, an elevated track comprising two rails carried thereby and insulated therefrom, a square shaft and a screw shaft parallel to said track, a car provided with separately insulated trucks running upon said rails, a motor supported upon one of said trestles, remote control means for causing said motor to turn one or the other of said shafts, a hoist carried by said car, a non-rotatable nut carried by said car engaging said screw shaft for propelling the car on said track, a gear slidably and non-rotatably mounted on said square shaft constrained to move with the car, an electromagnet suspended from said hoist, mechanism driven by said gear for operating said hoist and an electric circuit for energizing said electromagnet comprising said rails, said trucks and a pair of flexible conductors extending from said trucks to said electromagnet.

60 8. In a toy crane, a traveling car, a hoist on said car, propelling means for said car comprising

70

a screw shaft, operating means for said hoist comprising a square shaft, a reversible electric motor, gear shift means for connecting either of said shafts to said motor, a pair of electromagnets for operating said gear shift means, said electromagnets being connected in parallel circuits, a remote control panel having a connection to a power line and connections to said motor and said electromagnets, said panel having a switch for reversing said motor, a switch for selecting one or the other of said electromagnet circuits and a switch for starting and stopping said motor, whereby the car may be started in either direction and stopped and whereby the hoist may be started up or down and stopped.

9. A toy crane as defined in claim 8, comprising also a lifting magnet suspended from said hoist, circuit connections from said panel to said lifting magnet independent of said motor and said electromagnet circuits, and a switch on said panel for controlling said lifting magnet circuit connections.

10. In a toy crane, the combination of, an elevated track, trestle structure including spaced apart uprights supporting said track, a hoist, a carrier supporting said hoist movable along said track, a threaded shaft for impelling said carrier flanking said track rotatably supported by said structure, a thread follower on said carrier operably engaging said impelling shaft in a manner to translate rotary movement of the latter into rectilinear movement of said carrier along said track, a power shaft for motivating said hoist flanking said track and rotatably supported by said structure, a driven gear rotatably supported by said carrier operatively connected to said hoist, a driving gear in mesh with said driven gear slidably carried by said shaft in rotatably interlocked relation thereto, a constrainer on said carrier engaging said driving gear in a manner to maintain the same in mesh with said driven gear in various positions along said power shaft, and means for turning said shafts in either rotary direction at will.

11. In a toy crane, the combination defined in claim 10, together with a prime mover, and clutch mechanism for transmitting power therefrom to each of the said shafts selectively, said mechanism including separate driven clutch sections connected to rotate said shafts respectively and at least one driving clutch element connected to be powered by said prime mover constructed and arranged to engage with either of said driven clutch elements.

12. In a toy crane, the combination defined in claim 11, together with a clutch operating electro-magnet including an armature connected to cause clutching and unclutching relative movement between said driving clutch element and said driven clutch elements.

10

13. In a toy crane, the combination of, an elevated track, trestle structure supporting said track, a hoist, a carrier supporting said hoist movable along said track, a prime mover, motion transmitting mechanism operatively connected to said carrier, power transmitting mechanism operatively connected to said hoist, and a clutch for transmitting motion and power to each of said mechanisms selectively, said clutch including separate driven clutch sections operatively connected to said mechanisms respectively and at least one driving clutch section operably connected to said prime mover constructed and arranged to engage with either of said driven clutch sections.

14. In a toy crane, a square shaft and a screw shaft rotatably mounted in parallel relation, a reversible electric motor, driving connections from said motor to said shafts comprising an electrically operable clutch means for each of said shafts, a car having a non-rotating nut for engagement with said screw shaft to move the car lengthwise of said shafts, a gear slidably and non-rotatably mounted on said square shaft, said car also having a yoke embracing said gear, whereby the gear travels with the car, a hoist carried by the car, hoist operating mechanism driven by said gear, a remote control panel, means thereon for energizing either of said clutch means selectively, and means on said panel for reversing current flow through said motor.

15. In a toy crane, a square shaft and a screw shaft rotatably mounted in parallel relation, a reversible electric motor, driving connections from said motor to said shafts comprising an electrically operable clutch means for each shaft, a car having a non-rotating nut for engagement with said screw shaft to move the car lengthwise of said shafts, a gear slidably and non-rotatably mounted on said square shaft, said car also having a yoke embracing said gear, whereby the gear travels with the car, a hoist carried by the car comprising an electromagnet, hoist operating mechanism driven by said gear, a remote control panel, means thereon for energizing either of said clutch means selectively, for energizing or de-energizing said electromagnet and for reversing current flow through said motor.

FRED H. STICKLE.
